UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,263,627.

Specification of Letters Patent. Patented Apr. 23, 1918.

Application filed May 11, 1914. Serial No. 838,623.

To all whom it may concern:

Be it known that I, MILTON TIBBETTS, a citizen of the United States, and resident of Detroit, Wayne county, State of Michigan, have invented certain new and useful Improvements in Hydrocarbon-Motors, of which the following is a specification.

This invention relates to hydrocarbon motors and particularly to multi-cylinder motors. One embodiment of the invention is shown and includes a six cylinder motor in which there are two block castings of three cylinders each mounted on a suitable base or crank case.

15 One of the objects of the invention is to produce a multi-cylinder motor of clean external appearance, and one in which various parts of the motor are housed or inclosed.

20 Another object of the invention is to improve the water circulation system through the various jackets of the motor, carbureter, etc.

25 Another object of the invention is to improve the support and housing of the valve operating shaft.

Another object of the invention is to improve the valve and valve operating mechanism.

30 Other objects of the invention will appear from the following description taken in connection with the drawings which form a part of this specification, and in which:—

Figure 1 is a side elevation and vertical sectional view of a motor, embodying this invention;

Fig. 2 is a side elevation of the other side of the motor;

Fig. 3 is a plan view of the motor shown in Figs. 1 and 2;

Fig. 4 is a horizontal sectional view on the line 4—4 of Fig. 1;

Fig. 5 is a transverse vertical sectional view through one of the cylinders;

Fig. 6 is a transverse vertical sectional view through approximately the center of the motor;

Fig. 7 is an elevation of the valve shaft supporting piece which also comprises the intake header and wire housing with the cover secured thereto; and

Fig. 8 is a view of the reverse side of said valve supporting piece.

In the embodiment of the invention

shown herein, the motor comprises six cylinders cast in two blocks of three cylinders each. It will be understood that a lesser or greater number of cylinders may be employed and the cylinders may be otherwise cast.

Referring to the drawings, the base or crank case 10 is formed in two parts, the upper or supporting part 11 and the lower part or bottom cover 12. The cylinder blocks or castings are shown at 13, there being three cylinders 14 to each casting. These cylinders are supported upon the base or crank case 10 and the pistons 15 in the cylinders operate through connecting rods 16, the lower ends of which surround the crank pins 17 of the crank shaft 18 which is mounted in suitable bearings 19 in the crank case 10.

The upper ends of each of the cylinders 14 is somewhat contracted, as shown particularly in Figs. 1 and 5, forming a dome-shaped combustion space 20 immediately above the upper limit of travel of the piston 15. This contracted part of the cylinder is double walled and is of outward cylindrical form and constitutes a water-jacketed head for the cylinder. In it are arranged suitable inlet ports 22 and exhaust ports 23, preferably arranged in the same zone and both of which are adapted to be controlled by a cylindrical or sleeve valve 24. For the purpose of getting a more perfect fit for the valve 24, it is sometimes desirable to place a lining sleeve or collar 25 on the outside of the head 21, said lining sleeve of course being provided with inlet and exhaust ports alining with the ports 22 and 23 formed in the cylinder head.

The cylinder head 21 is also provided with a central depression or cavity 26 in which a spark plug 27 is suitably arranged in communication with the interior of the cylinder or combustion space 20. The central terminal 28 of the spark plug extends above the top of the cylinder head and the cavity 26 is closed by a suitable cap 29 of insulating material.

It will be seen that the cylinders 14 are water-jacketed as at 30 and this jacketing space continues up into the head 21. Water is supplied for cooling purposes by a pump 31 operated by suitable connections from the motor crank shaft 19, through pipes 32 and

33, to the lower part of each of the cylinder castings 13, as shown particularly in Fig. 2. There is a water outlet from each of the heads 21 as shown at 34 in Fig. 5, and 5 to all of these outlets is connected a pipe 35 which runs across the top of the cylinders and connects with a suitable radiator, not shown in the drawings. Of course it will be understood that the pump 31 draws the water from the bottom of the radiator through pipe 36 shown in Fig. 2, thus causing a constant circulation of water through the motor water-jackets and the radiator.

10 Each of the cylinder heads 21 is surrounded by a head piece 37 removably secured to the cylinder as by bolts 37', which head piece is double-walled to form a water jacket as shown in the various figures, and these head pieces 37 are substantially square 15 exteriorly, so that they will fit closely together on the tops of the cylinders and form a compact arrangement thereon.

It will be understood that a suitable cylindrical space is left between the exterior of each of the cylinder heads 21 and the interior walls of the head pieces 37, to form a valve chamber in which the valve 24 operates. As shown herein, this valve is rotated by suitable mechanism to control the inlet 25 and exhaust ports. The valve 24 is formed with one or two ports 38 which are adapted to register with the ports 22 and 23 for the purpose of controlling them preferably on the four stroke cycle principle.

30 Means are provided for supplying cooling water to the head pieces 37, either from the pump 31 as shown in Fig. 2 in full lines, or by an entirely separate circulation system which would include a slight modification 35 of the piping arrangement shown in Fig. 2. In the drawings, the jackets of the various head pieces 37 are connected in series by short sections of pipe 39 (see Fig. 2), and a pipe 40 leads from the pipe 33 to the lower 40 part of the head piece 37 of cylinder number 1, and an outlet pipe 41 leads from the upper part of the head piece 37 of cylinder number 6 to the water-jacketed part 42 of the carbureter 43. Also a pipe 44 leads 45 from the lower part of the carbureter water jacket to the water jacket of one of the cylinder castings 13. As above suggested, a modified form of this system comprises the elimination of pipes 44 and 40 and the substitution therefor of a pipe 45 shown in dotted lines in Fig. 2 as 50 extending from the lower part of the carbureter jacket 42 to the head piece 37 of cylinder number 1. By the latter arrangement, there would be a constant circulation 55 of water serially through the various head pieces, and from head piece number 6 through the pipe 41 and carbureter water jacket 42 and from there through the pipe 45 back again to head piece number 1. Thus

the cooling action of the carbureter 43 would act as a radiator for the heated water from the head pieces, while on the other hand the hot water passing through the water jacket of the carbureter would assist materially in 70 vaporization of the gasoline. With the system shown in full lines in Fig. 2, the water pumped into the pipe 33 would be divided therein, part of it going to the rear cylinder casting 13, part of it to the front cylinder 75 13 and some of it to the head pieces 37 through the pipe 40. Of course the heat in the cylinder water jackets and the head pieces, would materially aid in the circulation of the water through them.

80 For the purpose of rotating the valves 24, a valve operating shaft 46 is provided and is arranged longitudinally of the motor, adjacent each of the valves. The valves 24 have teeth 47 cut into them preferably within their circumference, thus forming worm gears on the valves, and the valve shaft 46 is provided with a series of worm wheels 48 adapted to mesh with the gears of the various valves.

90 In the drawings, a member 49 which is partly in the form of a casing, is provided with suitable bearings 50 for the valve shaft 46. This arrangement of the bearings for the valve operating shaft insures their being in proper alignment, and the shaft may be assembled in its bearings before the member 49 is mounted upon the motor. Figs. 7 and 8 illustrate the member 49 somewhat in detail, and upon reference thereto and to Figs. 1, 2, 3, 5, and 6, it will be seen that the member 49 is adapted to extend lengthwise of the motor and to be removably secured to each of the head pieces 37 as by bolts 51. It will also be seen that the member 49 is formed with an elongated opening 52 which exposes the valve operating mechanism when the member is in place on the motor, and this opening 52 is adapted to be closed by a suitable cover 53, 100 secured thereon as by screws or bolts 54.

105 Suitable means are provided for operating the valve operating shaft from the motor crank shaft 19, and in the present embodiment this means comprises a vertical shaft 55 shown in sections which are connected by universal joints 56. A tubular housing 57 surrounds the vertical shaft and is suitably connected at its upper end to the cover 53 as at 58, and at its lower end to 110 the crank case as at 59. The lower part of the vertical shaft 55 is mounted in suitable bearings 60 and the upper part is mounted in suitable bearings 61. A worm gear 62 on the vertical shaft 55 meshes with a worm gear 63 on the motor crank shaft 19, thus forming a driving connection between the motor crank shaft and the vertical shaft, and a worm gear 64 at the upper end of the vertical shaft 55, meshes with a worm gear 115 120 125 130

65 at the center of the valve operating shaft 46, thus forming a driving connection with the latter.

Upon reference to Figs. 1 and 5 to 8, it 5 will be seen that the member 49 has a cored out portion or passage 66 which is adapted to form the motor intake pipe or header. This pipe or passage 66 has an opening 67 for each of the head pieces 37 which permits the passage of gases from the intake pipe to and through ports 68 formed in each of the head pieces 37 in alinement with the intake port 22 in the heads 21. At the central part of the passage 66, is an opening 69 10 which communicates through a short pipe section 70 with the interior of the carburetor 43 hereinabove described. This arrangement is particularly well shown in Figs. 4 and 6 and it will be seen that the carburetor 43 is arranged substantially at the center of the motor between the two block castings 13 and directly inwardly of the tubular housing 57 for the vertical shaft 55.

The member 49 has also formed as an 25 integral part thereof, a casing or housing 71 which is open along one side and closed by a removable cover 72. Within this housing are suitably arranged the ignition wires 73 of the motor, and switches 74 lead from the 30 various wires to the terminals 28 of the spark plugs 27 hereinabove described. These switches 74 are preferably pivotally mounted upon the covers 72 as shown in the drawings.

35 From the above it will be seen that the member 49 extends lengthwise of the motor and forms a housing for the valve shaft and is also provided with channels or housings forming respectively the motor intake pipe and the casing for the ignition wires.

40 On the side of the motor opposite the ports 68, the head pieces 37 are formed with exhaust ports 75, and an exhaust pipe 76 is arranged lengthwise of the motor and connected to the head pieces 37 so that its interior communicates with each of said ports 75. It will be understood that the ports 75 are in alinement with exhaust ports 23 in the heads 21.

45 It will be further understood that the valves 24 are rotated or otherwise suitably operated through the gearing hereinabove described, to open and close the inlet and exhaust ports 22 and 23, so that the intake port only will be open on the first down stroke of the piston, both ports will be closed on the up stroke following, both ports will be closed on the next downward or firing stroke of the piston, and the exhaust port only open on the following upward or exhaust stroke thereof. In other words, the valves 24 will be operated in suitable relation to each other, so that each of the cylinders will fire on the four stroke cycle principle.

It will be further understood that various modifications of the embodiment of the invention herein shown may be made without departing from the spirit or scope of the invention.

Having thus described my invention, what I claim and desire to secure by Letters Patent is:—

1. In a hydrocarbon motor, in combination, a plurality of cylinders, a valve for 75 each of said cylinders, a valve operating shaft for the several valves, and a member extending lengthwise of the motor and having bearings for supporting said valve shaft.

2. In a hydrocarbon motor, in combination, a plurality of cylinders, a cylindrical valve coaxial with each of said cylinders, a valve operating shaft extending longitudinally of the motor and connected to operate said valves, and a removable member extending lengthwise of the valve shaft and having bearings for supporting said shaft in operative position. 80

3. In a hydrocarbon motor, in combination, a plurality of cylinders, a valve for 90 each of said cylinders, a valve operating shaft for the several valves, and a member extending lengthwise of the motor and having bearings for supporting said valve shaft independently of the cylinders. 95

4. In a hydrocarbon motor, in combination, a plurality of cylinders, a valve for each of said cylinders, a valve operating shaft for the several valves, and a member extending lengthwise of the motor and having bearings for supporting said valve shaft, said member and valve shaft being removable from the cylinders as a unit. 100

5. In a hydrocarbon motor, in combination, a plurality of cylinders side by side, 105 a removable head piece for each of said cylinders, a rotary valve for each of said cylinders, a valve operating shaft, gearing between said shaft and each of said valves, a housing for said valve shaft, and means for 110 securing said housing to each of said head pieces.

6. In a hydrocarbon motor, in combination, a plurality of cylinders, a valve for each of said cylinders, a valve shaft for driving said valves, a housing for said valve shaft, and a housing formed integrally with said valve shaft housing and inclosing the motor ignition wiring. 115

7. In a hydrocarbon motor, in combination, a plurality of cylinders, a valve for each of said cylinders, a valve shaft for driving said valves, and a member extending lengthwise of the motor for housing said valve shaft and having a channel formed 120 therein as a motor intake pipe. 125

8. In a hydrocarbon motor, in combination, a plurality of cylinders, a valve for each of said cylinders, a valve operating shaft, and a member extending lengthwise 130

- of the motor for housing said valve shaft and having channels formed therein, one of which channels acts as a housing for the ignition wires and the other as the motor intake pipe. 55
9. In a hydrocarbon motor, in combination, a plurality of cylinders, valves at the upper ends of said cylinders, a valve shaft for operating said valves, and a casing for 10 said valve shaft, said casing having a conduit formed therein above the valve shaft for housing the ignition wires and a conduit below the shaft forming the intake pipe. 60
10. In a hydrocarbon motor, the combination 15 with a block casting forming a plurality of cylinders each of which has an upward extension, of a sleeve fitted about said extension, and a valve sleeve adapted for operation on the first said sleeve. 65
- 20 11. In a hydrocarbon motor, the combination 25 with a block casting forming a plurality of cylinders each of which has an upward extension, of a sleeve or lining fitted and secured about said extension, a valve sleeve fitting over said lining and having ports co-operating with ports in the extension and lining, and means for rotating said valve sleeve. 70
12. In a hydrocarbon motor, in combination, a cylinder having an integral portion 30 of outward cylindrical form and ports through said portion, a sleeve valve surrounding said portion and having ports controlling the ports in said portion, and means 35 for rotating said valve comprising a worm gear at the upper end and within the circumference of said valve and a shaft having a worm in mesh with said gear. 80
13. In a hydrocarbon motor, in combination, 40 a cylinder having an integral contracted portion above the travel of the piston and ports through said portion, a sleeve valve surrounding said contracted portion and having ports controlling the ports in said 45 portion, and means for rotating said valve comprising a worm gear formed within the circumference of said valve above its ports and a shaft having a worm in mesh with said gear. 85
- 50 14. In a hydrocarbon motor, in combination, a plurality of cylinders comprising two blocks arranged adjacent each other, valves at the upper ends of said cylinders, a valve 90
- operating shaft and an intake pipe at the upper ends of said cylinders, a vertical shaft 55 connected to operate said valve operating shaft, and a carburetor connected to said intake pipe and arranged between said blocks and inwardly of said vertical shaft. 95
15. In a hydrocarbon motor, in combination, 60 a plurality of cylinders, a valve for each of said cylinders, a valve operating shaft for the several valves and universally jointed means for driving said shaft. 65
16. In a hydrocarbon motor, in combination, 65 a plurality of cylinders, a valve for each of said cylinders, a horizontally extending valve operating shaft for the several valves and vertically extending universally jointed means for driving said shaft. 70
17. In a hydrocarbon motor, in combination, 75 a plurality of cylinders, a valve for each of said cylinders, a valve operating shaft extending lengthwise of the motor and a vertically extending universally jointed shaft for driving said operating shaft. 80
18. In a hydrocarbon motor, in combination, 80 a plurality of cylinders cast in two blocks, a valve for each cylinder, a valve operating shaft for the several valves, a vertically extending shaft intermediate the cylinder blocks, and gearing connecting said last named shaft with said operating shaft. 85
19. In a hydrocarbon motor, in combination, 85 a plurality of cylinders cast in two blocks, a valve for each cylinder, a valve operating shaft for the several valves, a vertically extending universally jointed shaft intermediate the cylinder blocks and gearing connecting said last named shaft with 90 said operating shaft. 95
20. In a hydrocarbon motor, in combination, 95 a plurality of cylinders cast in two blocks, a valve for each cylinder, a valve operating shaft for the several valves, a housing extending lengthwise of the motor having bearings for supporting said shaft and a vertically extending universally jointed shaft mounted intermediate the cylinder blocks for driving said operating shaft. 100

In testimony whereof I affix my signature in the presence of two witnesses.
